SWITCH OPERATING LEVER

Tomlinson F. Johnson, Atlanta, Ga.

Application October 14, 1947, Serial No. 779,765

4 Claims. (Cl. 74—525)

1

This invention relates to high tension electric switches and has more particular reference to handles for operating such switches by remote control.

One object of the present invention is to provide an improved switch operating handle having the operating rod pivotally and slidably connected thereto to provide an adjustable throw.

Another object of the invention is to provide a switch operating handle as characterized above including means for locking the operating rod in its adjusted position.

A further object of the invention is to provide a switch operating handle as characterized above including a pivoted lever formed of two elongated flat metal strips secured together at their ends, a sleeve slidably adjustably mounted thereon and to which the operating rod is pivotally connected, and means for wedging and locking the strips within the sleeve to hold the sleeve in adjusted position.

Other objects and advantages of the invention will appear in the following specification when considered in connection with the accompanying drawings wherein:

Figure 1 is a side elevation of a switch operating handle constructed in accordance with the present invention;

Fig. 2 is a rear end elevation of the switch operating handle shown in Fig. 1;

Fig. 3 is a transverse sectional view taken on line 3—3 of Fig. 1;

Fig. 4 is a side elevational view showing one manner of mounting the switch operating handle shown in Fig. 1, and

Fig. 5 is a front view of the apparatus shown in Fig. 4.

In general the invention comprises an adjustable leverage device particularly adapted for use as a handle for operating high tension electric switches and the like by remote control. High tension electrical switches, either singly or as a group or gang are usually mounted on poles or towers and are opened and closed by means of an elongated and sometimes sectional push-pole or operating rod having its upper end operatively connected to the switch or switches and having its lower end pivotally connected to a pump type handle comprising an arm or lever pivotally mounted on the pole or tower. The handle may be a standard pump type handle, i. e., a lever of the second class or a reversible pump type handle, i. e., a lever of the first class.

Referring now to the drawings, there is shown in Figs. 1 and 2 a preferred embodiment of a

2

switch operating handle constructed in accordance with the present invention. As shown, the switch operating handle comprises an arm or lever 10 formed of two elongated superposed flat metal strips 11, 12 secured together at one of their ends as by means of a bolt and lock nut assembly 13 and at the other of their ends by means of a bolt 14 which extends through the members and is threaded into a hand-engaging element or handle 15. The lever 10 is provided with means enabling it to be pivotally mounted on a bracket or support with the pivot point located at one end of, or intermediate to the ends of, the assembly.

15 In the particular embodiment shown, the strips 11, 12 are provided intermediate their ends with aligned openings 16, 17 through which a short piece of pipe 18 extends and is secured by being welded to one of the strips. The pipe 18 provides 20 a hub by means of which the lever may be pivotally mounted in a manner hereinafter to be described.

An adjustable sleeve 19 is slidably mounted on the lever 10 and may be positioned on either side 25 of the pipe 18 depending on whether the switch operating handle is of the standard or reversible type. In the particular embodiment illustrated the handle is shown as a standard pump type, however, in Fig. 4, the manner in which the sleeve 30 would be mounted for a reversible pump type is shown in phantom.

The sleeve 19 is substantially rectangular in outline and in cross section and is provided with four bosses; a spaced pair 20, 21 located on one 35 side in horizontal alignment with a spaced pair 22, 23 located on the opposite side. The bosses are provided with screw threaded openings 24 for the reception of threaded set screws 25. Preferably and as shown, the set screws 25 are of the type shown and described in my Patent No. 2,274,899 issued March 3, 1942, for Connecting 40 means and each comprises a threaded body portion having the usual non-circular head and a reduced and slightly tapered non-threaded frusto-conical end portion 26 having a biased cut end 27.

The sleeve 19 is slidably adjustably mounted on the lever 10 and the set screws are employed to 45 lock the sleeve in its adjusted position. After the sleeve 19 has been positioned on the lever, the set screws are rotated in the proper direction to cause the inner ends thereof to engage the abutting edges of the strips 11 and 12. Continued 50 rotation of the set screws will cause the lower 55 rotation of the set screws will cause the lower

leading edge of the bevelled ends to cut a groove in the abutting walls of the strips 11 and 12. As the screws advance, the tapered end portions 26 will be forced between the strips, spreading them apart and wedging them inside the sleeve 19 as shown in Fig. 3.

In addition to the wedging of the strips 11 and 12 within the sleeve to prevent relative motion therebetween, the tapered end portions 26 are partially embedded in the grooves cut in the opposing walls of the strips thereby positively locking the sleeve on the strips.

The sleeve 19 has an enlarged apertured boss 28 formed integral therewith. A pivot pin 29 is fixedly mounted on the boss 28 and has its outer free end provided with a circumferential groove 30. A collar 31, provided with an ear 32 having an opening 33 therethrough, is pivotally mounted on the sleeve 19 with the pivot pin 29 extending through the opening 33 and retained thereon by means of a split washer 34 inserted in the groove 30 on the end of the pivot pin.

The bottom end of the usual operating rod 35 is slidably received in the collar 31 and is locked therein as by means of a pair of set screws 36 threaded through screw thread openings in bosses 37 formed on the collar. The operating rod 35 preferably, and as shown, is in the form of a hollow tubular member or pipe. The set screws 36 and the manner in which they engage the operating rod 35 to lock it in the collar is similar to the construction and operation of the set screws and collar shown in my above-referred to Patent No. 2,274,899.

The lever 10 is adapted to be pivotally mounted on a support, which may be a pole or a tower, and with the pivot located at one end of the lever or at a point intermediate of its ends. In the particular embodiment illustrated, the lever is shown as mounted on a spaced pair of V-shaped brackets 38 which have the ends of their legs secured as by bolting to the legs of a channel member 39 which in turn is secured by bolting to a support 40 which may be a structural part of a tower or a pole.

The vertex or forward end of each of the V-shaped bracket members has an opening 41 formed therein and has an integral elongated flat plate 42 formed thereon. The plates 42 have spaced openings 43, 44 formed therein which are in vertical alignment with the opening 41. The lever 10 is mounted between the bracket members 38 with the pipe 18 aligned with the openings 41 formed in the bracket members and a pivot pin 45 having an enlarged head 46 extends through the openings 41 in the brackets 38 and through the pipe 18 and is retained in place as by means of a split pin.

A locking pin 47 permanently attached to one of the bracket members as by a chain, may be provided to lock the lever 10 when raised to close the switch. The lever then being in a vertical position and having an opening 48 formed therein aligned with the upper openings 43 formed in the plates 42. The locking pin may also lock the lever when lowered to open the switch as the lever will then be in a vertical position with the opening 48 therein aligned with the lower openings 44 formed in the plates 42.

From the foregoing it readily will be seen that there has been provided a switch operating handle, which is adapted to be mounted on any suitable support and which may be used as either a standard or reversible type and with the operating rod pivotally and slidably connected to

the lever to permit adjustment of the throw of the handle and with locking set screws to positively lock the device in its adjusted position.

Obviously, the present invention is not restricted to the particular embodiment thereof, herein shown and described.

What is claimed is:

1. A handle for operating high tension electric switches and the like, comprising in combination, a pivotally mounted lever formed of at least one elongated flat metal strip; a sleeve having an operating member pivotally connected thereto, said sleeve being slidably mounted on said lever intermediate one end thereof and its pivot, whereby the throw of said operating member may be adjusted; and wedging and locking means carried by said sleeve, said means including at least one pair of opposing set screws, each of said screws comprising a threaded shank having means for turning it at one end and an integral smooth frustro-conical extension of reduced diameter at the other end provided with a biased end portion adapted to cut a groove into the adjacent side wall of said strip, whereby said extension will wedge said strip against the inner wall of said sleeve with a portion of said extension remaining in said groove to positively lock said sleeve in its wedged position on said lever.

2. A handle for operating high tension electric switches and the like, comprising in combination, a pivotally mounted lever, formed of two elongated, superposed flat metal strips secured together at their ends; a sleeve slidably mounted on the lever; wedging means mounted on said sleeve and adapted to be moved to engage and spread apart the abutting walls of said strips within said sleeve, thereby wedging said sleeve on said lever; a collar pivotally mounted on said sleeve; and a switch operating member having one end mounted in said collar.

3. A handle for operating high tension electric switches and the like as set forth in claim 2, wherein said wedging means comprises at least one pair of opposing set screws, said screws having reduced plain end portions, positioned to be moved between said strips to spread them apart, thereby wedging said sleeve on said strips.

4. A handle for operating high tension electric switches and the like as set forth in claim 2, wherein said wedging means includes at least one pair of opposing set screws, each of said screws comprising a threaded shank having means for turning it at one end; and an integral smooth frustro-conical extension of reduced diameter at the other end provided with a biased end portion adapted to cut a groove into the abutting walls of said strips, whereby said extension will spread said strips apart to wedge the sleeve on the strips and said hardened extensions on the end of the screws will remain in said grooves to positively lock said sleeve in its wedged position on said lever.
